CLAIM

The ornamental design for a portable fan display screen displaying graphical user interface, as shown and described.

DESCRIPTION

FIG. 1 is a first image in a sequence for a portable fan display screen displaying graphical user interface according to an embodiment of our new design;

FIG. 2 is a second image thereof;

FIG. 3 is a third image thereof;

FIG. 4 is a fourth image thereof;

FIG. 5 is a fifth image thereof;

FIG. 6 is a sixth image thereof;

FIG. 7 is a seventh image thereof;

FIG. 8 is a eighth image thereof;

FIG. 9 is a ninth image thereof;

FIG. 10 is a first image in a sequence for the portable fan display screen displaying graphical user interface according to a second embodiment of our new design;

FIG. 11 is a second image thereof;

FIG. 12 is a third image thereof;

FIG. 13 is a fourth image thereof;

FIG. 14 is a fifth image thereof;

FIG. 15 is a sixth image thereof;

FIG. 16 is a seventh image thereof;

FIG. 17 is a eighth image thereof;

FIG. 18 is a ninth image thereof;

FIG. 19 is a first image in a sequence for the portable fan display screen displaying graphical user interface according to a third embodiment of our new design;

FIG. 20 is a second image thereof;

FIG. 21 is a third image thereof;

FIG. 22 is a fourth image thereof;

FIG. 23 is a fifth image thereof;

FIG. 24 is a sixth image thereof;

FIG. 25 is a seventh image thereof;

FIG. 26 is a eighth image thereof; and,

FIG. 27 is a ninth image thereof.

The broken line showing of the portable fan display screen displaying graphical user interface is included for the purpose of illustrating portions of the article and forms no part of the claimed design. The appearance of the transitional image sequentially transitions between the images shown in FIGS. 1-9, 10-18, and 19-27. The process or period in which one image transitions to another image forms no part of the claimed design.
